UNITED STATES PATENT OFFICE.

RALPH S. HAMILTON, OF PROVIDENCE, RHODE ISLAND, ASSIGNOR TO HAMILTON & HAMILTON, JR., OF PROVIDENCE, RHODE ISLAND, A FIRM.

FASTENER.

SPECIFICATION forming part of Letters Patent No. 764,238, dated July 5, 1904.

Application filed February 3, 1904. Serial No. 181,381. (No model.)

To all whom it may concern:

Be it known that I, RALPH S. HAMILTON, a citizen of the United States, residing at Providence, in the county of Providence and State of Rhode Island, have invented a new and useful Improvement in Fasteners, of which the following is a specification.

This invention has reference to an improvement in fasteners adapted to secure or fasten articles to wearing-apparel or to fasten articles of wearing-apparel together.

In fasteners for securing articles of value to wearing-apparel it is essential that the fastener should be firmly and positively secured when in use and easily released by the wearer when desired.

The object of my invention is to improve the construction of a fastener whereby the fastener is firmly secured and easily released, and a pull on the fastener by accident or other means tends to more firmly secure the fastener to the wearing-apparel than has heretofore been done.

My invention consists in the peculiar and novel construction of a fastener having substantially a U-shaped frame, an opening in the front of the frame, bearings on the sides and eyes on the ends of the frame, all formed integral with the frame, a cam-shaped fastening-arm with teeth extending through the opening in the frame and pivotally secured off center in the frame-bearings, and a coiled spring surrounding the pivot-pin and adapted to exert a spring tension on the fastening-arm to hold the fastening-arm in the closed position, as will be more fully set forth hereinafter.

Figure 1 is an enlarged front view of my improved fastener, showing the position of the coiled spring in the fastener. Fig. 2 is a side view of the fastener, showing the fastening-arm in the normal or closed position. Fig. 3 is a back view of the fastener. Fig. 4 is a still further enlarged sectional view taken on line X X of Fig. 1, showing the fastening-arm in the closed position in full lines and in the open position in broken lines. Fig. 5 is a plan view of the blank forming the frame of the fastener, and Fig. 6 is a plan view of

the blank forming the cam-shaped fastening-arm.

In the drawings, *a* indicates the frame, *b* the cam-shaped fastening-arm, *c* the pivot-pin, and *d* the coiled spring of my improved fastener. The frame *a* is stamped from sheet metal and bent substantially U-shaped to form the front *a'* and the back *a''*. The opening *a³*, the bearings *a⁴ a⁴*, bent inwardly at right angles to the frame, the eye *a⁵* on the front, and the eye *a⁶* on the back are all formed integral with the frame *a*. The metal of the frame at the bearings is upset to bring the center of the bearing practically on a line with the center of the front *a'*. The fastening-arm *b* is stamped from sheet metal and has the enlarged semicircular cam-shaped ends *b' b'* with the teeth *b³ b³*, the holes *b³ b³* for the pivot-pin *c*, and the hole *b⁴* for one end of the coiled spring *d*. The blank for the fastening-arm *b* (shown in Fig. 6) is bent in the center to bring the ends *b' b'* into the position as shown in Fig. 1, forming the projecting arm *b⁵* and a space between the ends *b' b'* for the coiled spring *d*, which has the straight end *d'* and the bent end *d''*.

The fastening-arm *b* is pivotally secured in the opening *a³* by the pivot-pin *c*, which passes through the bearings *a⁴ a⁴* in the frame, the holes *b³ b³* in the fastening-arm, and the coiled spring *d*. The straight end *d'* of the spring rests on the front *a'* of the frame, and the bent end *d''* enters the hole *b⁴* in the fastening-arm *b* and exerts a spring tension on the fastening-arm to hold it in its normal or closed position. The upper edge *a⁷* of the opening *a³* forms a stop to limit the inward movement of the fastening-arm.

In the operation of my improved fastener the fastener is secured automatically by forcing the fastener downward over the fabric. The edge of the fabric acts on the cam-shaped ends *b' b'* of the fastening-arm *b* to force the fastening-arm outward against the tension of the coiled spring *d*. When the fabric reaches the closed end of the fastener, the tension of the spring *d* on the fastening-arm forces the teeth *b³ b³* on the cam-shaped end of the fastening-arms into the fabric, and this may be

assisted by pressure on the projecting arm b^5 of the fastening-arm. The fastener may be instantly released from the fabric by moving the fastening-arm outward into the position 5 as shown in broken lines in Fig. 4.

The fastener when once secured to the fabric is practically locked and cannot be released except by moving the fastening-arm outward against the tension of the coiled spring d .

10 An upward movement of the fastener by accident or other means would tend to force the teeth $b^2 b^3$ on the fastening-lever more firmly into the fabric.

The semicircular ends of the fastening-arm being pivoted off center act as cams to pinch the fabric between the back of the fastener and the fastening-arm. It is evident that the teeth on the fastening-arm could be modified or dispensed with and a smooth edge used on 20 the cam ends of the fastening-arm without materially affecting the spirit of my invention.

Having thus described my invention, I claim as new and desire to secure by Letters Patent—

25 1. In a fastener, a frame stamped from sheet metal and bent substantially U-shaped; a fastening-arm stamped from sheet metal and bent to form two adjacent semicircular ends pivotally secured off center in the frame, and a coiled spring adapted to exert a spring tension on the fastening-arm, as described.

2. In a fastener, a frame stamped from sheet metal and bent substantially U-shaped to form the front and back of the fastener, there being an opening in the front, bearings and an eye formed on the front and an eye formed 35 on the back of said U-shaped frame, a fastening-arm stamped from sheet metal and bent to form two adjacent semicircular ends with off-center pivot-holes, a pivot-pin, and a coiled spring adapted to exert a spring tension on 40 the fastening-arm, as described.

3. In a fastener, the combination of the frame a having the front a' , the back a'' , there being an opening a^3 in the front, the bearings $a^4 a^4$ on the sides, and an eye a^5 on the front 45 and an eye a^6 on the back, and the edge a^7 forming a stop, all formed integral with the frame, the fastening-arm b having the semicircular ends $b' b'$ with the teeth $b^2 b^3$, the off-center pivot-holes $b^8 b^9$ and the hole b^4 , the projecting arm b^5 , the pivot-pin c , and the coiled spring d having the straight end d' and the bent end d'' , all as shown and described.

In testimony whereof I have signed my name to this specification in the presence of two sub- 55 scribing witnesses.

RALPH S. HAMILTON.
